Application September 21, 1938, Serial No. 230,946

23 Claims. (Cl. 200—150)

This invention relates to circuit interrupters and, more particularly, to high power circuit breakers of the liquid immersed type. In general, control of the arc after it is drawn is the chief consideration in bringing about effective arc extinction in circuit breakers of all types. In liquid immersed interrupters, the element which is of prime importance in obtaining arc control involves securing relative motion between the arc and the arc extinguishing liquid. This relative motion may be obtained either by moving the arc through a quantity of liquid or by holding the arc stationary and moving the liquid with respect to the arc. In the latter method, there are two general directions of moving the liquid relative to the arc stream. Perhaps the most apparent is a cross blast where the liquid is moved in a direction perpendicular to the arc and an attempt is made to break the continuity of the arc stream by inserting a sheet or film of liquid insulation.

This method of controlling the arc, however, is objectionable in that it frequently causes high arc voltage, sudden peaks of arc energy and the forcing of a current zero with accompanying voltage surges and mechanical shocks.

I have discovered that arc control involving the flow of arc extinguishing liquid longitudinally of and in close proximity to the arc stream produces superior results and this is the method which forms the basis of the present invention. More specifically, when the motion of the arc extinguishing liquid is parallel to the arc, there is little tendency for the moving liquid to interfere with the flow of current other than at zero, thus keeping the arc energy and gas generation to a minimum value. The longitudinal flow of arc extinguishing liquid also rapidly removes the excess gas from around the arc as it is generated so that as the current approaches its zero value, the last small filament of arc may be regarded as passing through a small hole or chimney in the arc extinguishing liquid. Since the liquid is under considerable pressure and adequate means are provided for the small amount of generated gas to escape freely, it may be assumed that the wall of liquid surrounding the gas moves toward the arc as the gas bubble contracts with the decrease in current in the cyclic variation. When the diameter of the hole through the arc extinguishing liquid becomes small, especially near the current zero, the process of deionization by diffusion to the surrounding cooled liquid is greatly accelerated.

Soon after the current reaches its zero value

and before the generated voltage can shift from the circuit reactance to the arc terminals, the ionization in the remaining gas is reduced to a very small value. Since the re-ignition or breakdown voltage through this last thread of gas varies inversely with the degree of ionization in the gas and directly with the absolute pressure on the gas, it is evident that a large number of volts per inch of arc length may be interrupted without danger of breaking the continuity of the arc path just preceding the normal current zero. This insures consistent arc extinction and avoids the rapid increase in arc voltage which causes a premature current zero and a resulting voltage surge.

The main object of my invention is the provision of an improved circuit breaker structure wherein circuit interruption is accomplished in accordance with the aforesigned principles.

Another object of my invention is the provision of a circuit breaker capable of interrupting a large number of volts per inch of contact separation without generating appreciable arc energy and with a minimum of arc extinguishing liquid deterioration.

A further object of my invention is the provision of a circuit interrupter, the performance of which is substantially consistent over the entire current range regardless of power factor or type of circuit being interrupted.

A more specific object of my invention is the provision of a circuit breaker embodying a circuit interrupting element wherein the established arc is maintained in a fixed position and subjected to a longitudinal flow of arc extinguishing liquid without destroying the continuity of the arc stream and the arc is maintained at a relatively low pressure during the major portion of the arcing period after which the pressure on the arc stream is materially increased.

Other objects and advantages relate to details of the interrupter structure and the arrangement of the various parts thereof, all of which will appear more fully in the following description when taken in connection with the accompanying drawings, in which

Figures 1 and 2 are side elevation views partially in section which jointly show the circuit interrupter of my invention, the upper section being shown in Fig. 1 and the lower section in Fig. 2.

Fig. 3 is a longitudinal sectional view of the interrupting assembly of my breaker in the closed circuit position.

Fig. 4 is a longitudinal sectional view of the interrupting assembly in the open circuit position.

Fig. 5 is a longitudinal sectional view showing the movable contact carrying member of the interrupting assembly on a slightly reduced scale.

Fig. 6 is a fragmentary sectional view showing details of the disconnect contacts between the operating mechanism and the movable contact carrying member, and

Figs. 7 to 10 are cross sectional views of the interrupting assembly taken respectively along the lines VII—VII, VIII—VIII, IX—IX, X—X of Fig. 4.

Referring to the drawings, the reference numeral 11 designates a fabricated steel support having a base plate 13 which carries the entire circuit breaker structure. The base plate 13 carries a tubular insulator 15 of weather-proof material, such as porcelain or the like. Concentrically disposed within the insulator 15 is a tubular strain member 17 of insulating material having a metallic collar 19 disposed at each end thereof. The lower collar 19 serves as an anchoring means for securing the strain member 17 to the base plate 13. A flange casing member 21 rests upon the upper end of the insulator 15 and is held in place by means of an annular plate 23 secured by bolts 25 to the upper collar 19 of the strain member 17. The tubular strain member 17 thereby maintains the insulator 15 in position and relieves it of all strain except those which occur in compression. The flange casing 21 is provided with a cover plate 27 so as to form a complete enclosure or compartment within the tubular strain member 17. This compartment is sealed and adapted to house the current transformer of the interrupter generally indicated at 29. Inasmuch as the specific construction of the current transformer 29 forms no part of the invention, it need not be further described.

Mounted upon the cover plate 27 is a metallic casing 31 having a top plate 33 which supports a second tubular insulator 35 also of weather-proof material, such as porcelain or the like. Disposed within the insulator 35 is a second strain member 37 having metallic collars 39 at each end thereof similar in construction to the collars 19 and the strain member 17. The tubular strain member 37 is secured to the support plate 33 by means of stud bolts 41 threaded into the collar 39. An annular bearing plate 43 resting on the upper end of the insulator 35 in conjunction with the annular support plate 45 and the bolts 47 serve to join the upper end of the insulator 35 to the tubular strain member 37. Thus the strain member 37 also maintains the weather-proof insulator 35 in compression and relieves the latter of all other strain. The bearing plate 43 carries a dome-like closure 49 for closing the upper end of the interrupter housing.

The space within the tubular strain member 37 is utilized as an interrupting compartment for housing an interrupting assembly 51 of the circuit breaker. The interrupting assembly 51, as more clearly shown in Fig. 3, comprises two interrupting elements 53 and 55 disposed in axial alignment and joined by a metallic flange section 57. The upper end of the interrupting element 53 is provided with a flanged casing member 59 having outwardly projecting support arms 61. The support arms 61 carry the entire weight of the circuit interrupting assembly and are adapted to be bolted to the annular ring 45 so as to suspend the interrupting assembly 51 with-

in the tubular strain member 37. Thus, the entire circuit interrupting assembly may readily be removed and replaced from the circuit breaker housing for the purpose of inspection, repair or adjustment. The circuit interrupting elements 53 and 55 are constructed of tubular members 63 of insulating material which have metallic collars 65 screw threaded to each end thereof. The metallic collars 65 serve as means in conjunction with suitable bolts, as shown, for joining the two interrupting elements to each other and also for joining the elements to the flange support 59.

Each of the tubular sections 63 carries a plurality of annularly shaped plates or washers 67 and 69 alternately disposed in stacked relation and of insulating material, preferably fiber or other material, which will resist the direct action of an arc thereon. The inside diameter of the washers 67 are smaller than the inside diameters of the washers 69 so as to provide an arc chamber 71 having a corrugated surface. It will be noted that the larger washers 67 of the interrupting element 55 have an inside diameter which is larger than the inside diameter of the plate 67 in the interrupting element 53. Thus the general diameter of the arc chamber 71 of the interrupting element 55 is larger than that in the interrupting element 53, the purpose of which will appear more fully hereinafter.

Disposed between the flange support 59 and the upper collar 65 of the interrupting element 53 is a fixed contact support 73, in this instance carrying four resilient contact fingers 75. The contact fingers 75 are connected by means of flexible shunts 77 to the flange support member 59. A second fixed contact support 73 is also disposed between the flange spacing member 51 and the upper collar 65 of the interrupting element 55. This second fixed contact support also carries four flexible contact fingers 75. In the latter instance, however, these contacts are connected by flexible shunts 79 to a movable contact member which will be explained more fully hereinafter.

The moving contact assembly is carried by a rod-like operating member generally indicated at 81 extending longitudinally through the interrupting elements 53 and 55. The operating member 81 is more clearly shown in Fig. 5 and constitutes a central support member 83 of insulating material having a threaded metallic fitting 85 secured to each end thereof. To the lower metallic fitting 85 is screw threaded a metallic cap member 87 which, in turn, supports a contact ring 89 having three main current carrying contacts 91 and an arcing contact 93 formed thereon. Surrounding the support rod 83 is a sleeve 95 of insulating material which is highly arc resistant. Surrounding the sleeve 95 and adjacent the contact ring 89 are a plurality of washers 97 and 99 alternately disposed and having different outside diameters so as to present a corrugated external cylindrical surface. Adjacent the group of washers 97 and 99 at the lower end of the sleeve 95 is a metallic sleeve 101, the lower end of which has a squared recessed portion 103 to which the ends of the flexible shunts 79 are connected. The upper end of the conducting sleeve 101 supports a second contact ring 89 of somewhat smaller diameter than the ring at the lower end of the assembly. The upper contact ring 89 is also provided with three main current carrying contacts 91 and a single arcing contact 93. Disposed about the upper contact ring 89 is a second series of

fiber washers 97 and 99 similar to those previously described, with the exception that washers 97 in this instance have a smaller outside diameter. Immediately above the second series of washers 97 and 99 is a metallic guide sleeve 105 screw threaded to the upper metallic fitting 85 of the support rod 83. Thus the sleeve 105, when screwed into clamping engagement with the upper plate assembly, holds the entire assembly rigidly together as a unit.

It will be noted that the contacts 91 and 93 of the upper contact ring 89 are adapted to register with the contact finger 75 on the circuit interrupting element 53 when the interrupter is in the closed circuit position, as shown in Fig. 3. Likewise, the contacts 91 and 93 of the lower contact ring 89 engage the contact fingers 75 of the lower interrupting element 55. Thus, as shown in Fig. 3, an electrical circuit is established from the flanged support 59 through the flexible shunts 77 to the contact finger 75, the upper contact ring 89, the conducting sleeve 101, the flexible shunt 79 to the contact finger 75 of the interrupting element 55 to the contacts 91 and 93 of the lower contact ring 89, and finally to the metallic cap 81. When the circuit interrupting assembly 51 is positioned within the housing, as shown in Fig. 1, external circuit connections from the flange support 59 are made by means of a flexible shunt 107 to a terminal stud 109 passing through the side of the dome-shaped cover 49.

The cap member 81 of the movable operating member 81 is provided, as shown more clearly in Fig. 6, with a disconnect contact assembly housed within the collar 111 screw threaded thereto. The collar 111 is provided with a plurality of contact fingers 112 adapted to make sliding engagement with a bayonet type contact 115 carried by the upper end of an actuating member 117. The actuating member, the operation of which will be more fully described hereinafter, is of conducting material and has connected thereto at its lower end (Fig. 1) a flexible shunt 118 which, in turn, connects to a terminal stud 121 passing through the side wall of the casing 31. To connect the current transformer 29 in the breaker circuit, an external connection as shown at 123, is made from the terminal stud 121 to a similar terminal stud 125 passing through the flanged casing 31. The flange casing 31 is also provided with the second terminal stud 127 in this instance insulated from the casing by a bushing 128. The inner ends of the terminal studs 125 and 127 are respectively connected by suitable leads 131 and 133 to the current transformer 29.

The operating member 81 is arranged for reciprocating movement axially of the circuit interrupting elements 53 and 55. It is moved downwardly to the open circuit position by means of a battery of compression springs 135 disposed between a fixed pressure plate 137 and a movable pressure plate 139. The fixed pressure plate 137 is secured to the upper ends of a plurality of guide and support rods 141 anchored in the support arms 61. The lower and movable pressure plate 139 is secured to a screw threaded portion 143 of the guide sleeve 105 forming the upper end of the operating member 81 and is provided with suitable apertures through which the support rods 141 may pass and serve to guide the plate during its reciprocal movement.

The operating member 81 is held in the closed position against the action of the springs 135, as shown in Fig. 3, by a suitable actuating mechanism connected to the operating member 117, as

more clearly shown at 145 in Fig. 1. The actuating mechanism 145 constitutes a plurality of linkages for producing substantially straight line motion of the operating member 117. The actuating mechanism 145 is controlled by a pull rod 147 coupled thereto and which extends downwardly through the current transformer compartment within the tubular casing 17. The pull rod 147 is sealed with respect to the casing by means of a tube 149, the upper end of which is joined in a liquid-tight manner to the coverplate 27, whereas the lower end is joined in a similar manner to the base plate 13. The lower end of the pull rod 147 is coupled to an arm 149, which, in turn, is secured to a torsion shaft 151 having an actuating arm 153 which is adapted to be coupled to a suitable breaker operating mechanism. The right-hand side of the torsion shaft 151 and the arm 149 are disposed within a liquid tight chamber 155. From the foregoing description, it is apparent that the operating mechanism and the interrupting assembly 51 is submerged in an arc extinguishing liquid which is maintained separate and apart from the insulating liquid contained in the transformer chamber within the tubular casing 17.

Upon release of the actuating mechanism 145, the springs 135 force the operating member 81 downwardly to the position shown in Fig. 4. The operating member 117, however, due to actuation of the actuating mechanism 145, as controlled by the pull rod 147, continues its downward movement until the lower end of the actuating member 117 strikes the stop 157 provided on the upper side of the cover plate 27, as shown in Fig. 2. The travel of the operating member 117 is greater than that of the cooperating member 81 and thus produces a disconnect gap between these members when the interrupter is in the open circuit position. This disconnect takes place between the spring pressed contact fingers 118 carried by the collar 111 at the lower end of the operating member 81 and the bayonet contact 115 carried by the upper end of the operating member 117.

During the closing movement of the interrupter, the actuating mechanism 145, operated by the pull rod 147, raises the member 117 so that the contact 115 engages the spring pressed contacts 118 to complete the electrical circuit between the operating member 81 and 117. A slight buffing action is provided to lessen the shock to the connected mechanism during engagement of the two operating members 81 and 117 by the use of a shock absorbing member 153 secured within the collar 111 and spring pressed in a direction towards the bayonet contact 115 and against which the contact 115 strikes during its upward movement. Further upward movement of the operating member 117 causes the member 81 to be moved against the action of the springs 135 to the closed position. Inasmuch as the actuating mechanism 145 is adapted to quickly release the operating member 81, the downward movement of that member occurs at a relatively high speed. This high speed motion is arrested at the end of the opening stroke by means of a buffer-plate 161 disposed in the path of movement of the pressure plate 139 and guided by the support rods 141. The buffer plate 161 is resiliently urged towards the pressure plate 139 by springs 163 encircling the support and guide rods 141.

The operating member 81 is further guided during its reciprocating movement at its upper end by the closure plate 165 secured to the upper

end of the support flange 59. In order to prevent binding of the guide sleeve 105 as it passes through the cover plate 165, the guide sleeve 105 is grooved circumferentially, as shown. The operating member 81 is also guided by a closure plate 167 secured between the lower collar 65 of the interrupting element 53 and the flange casing 57. The aperture in the closure plate 167 through which the conducting sleeve 101 of operating member 81 is adapted to slide, is provided with an annular recess 168 which has its innermost wall tapering towards the sleeve 101 so as to provide a knife like scraping edge adjacent the sleeve. This scraping edge maintains the sleeve 101 free from foreign matters such as may occur from the establishment of an arc within the arc chamber 71 during circuit interruption and thus prevents the sleeve 101 from binding as it passes through the closure plate 167. A similar scraping device is provided in the form of a guide annulus 171 at the lower end of the circuit interrupting element 55 having a scraping edge 173 and which serves to guide the operating member 117 and the cap member 87 during reciprocating movement and also keeps the bearing surfaces of these latter members free from foreign matter.

As shown more clearly in Figs. 7 to 10, the arc chambers as defined by the washers 67 are of generally circular cross section. It should be noted that the arcing contacts 93 carried by the two contact rings 89 extend a short distance laterally from their respective contact rings. The washers 67 are provided with notched portions 175 to provide an elongated groove or passage into which the arcing contacts 93 are adapted to be moved during the opening movement of the interrupter. The washers 97 on the member 81 have a diameter such that there is but slight clearance between these washers and the washers 67 defining and limiting the side walls of the arc chambers 71. The outside diameter of the insulating washers 97 of the upper group is slightly greater than the outside diameter of the guide sleeve 101. Thus when the operating member 81 is moved downwardly, arc extinguishing liquid within the upper arc chamber 71 will be displaced upwardly about the arcing contact 93 and longitudinally of the notched portion 175.

Any tendency of the washers 97 on the member 81 to interlock with the washers 67 forming the arc chambers 71 due to lateral displacement of the member 81, is avoided by making the washers 97 of slightly greater thickness than the washers 67 as shown. It will, of course, be obvious that the same result is obtained by making the washers 67 of greater thickness than the washers 97. The desired result may also be obtained by using a different spacing between the stationary washers 67 than between the movable washers 97.

It should also be noted that the guide sleeve 105 is of less diameter than the washers 97. Thus when the operating member 81 is moving downwardly, a greater volume of material, as constituted by the washers 97 and 99, is moved into the arc chamber 71 and out of the space between the arc chamber 71 and the closure plate 165 than is moved into the space by the guide sleeve 105, causing a partial evacuation of this space. The space above the arc chamber 71 in the interrupting element 53 may be designated as an expansion chamber 177 into which arc gases resulting from an arc drawn between the arcing contact 93 and its corresponding fixed contact finger 75 may escape. Flow of arc gases into the

expansion chamber 177 is also augmented by virtue of the partial evacuation within the chamber as above described.

In order to relieve the chamber 177 of excess pressure during the latter part of the arcing period and also to provide means for the in flow of arc extinguishing liquid following arc extinction, a vent opening is provided through the side wall of the tubular member 63, as shown at 179. The vent opening 179 is so proportioned that during the initial opening movement of the operating member 81, partial evacuation will take place at a rate greater than the in flow of arc extinguishing liquid from the arcing space 71 tending to displace the evacuated space.

In connection with the interrupting element 55, the relative proportion between the diameters of the washers 97, the connecting sleeve 101 and the cap member 87 are maintained, as in the interrupting element 53, that is, the washers 97 are of slightly greater diameter than the cap member 87 and the upper end of the operating member 117. This arrangement provides a piston for forcing arc extinguishing liquid longitudinally of the notched path 175 of the arc passage 71. Likewise the external diameter of the conducting sleeve 101 is of smaller diameter than the external diameter of the washers 97. Thus the space between the lower arc chamber 71 and the closure member 167 forms a second expansion chamber 181 which is slightly evacuated during the opening movement of the operating member 81 so as to cause a ready escape of the gas from the arc chamber 71 into the expansion chamber. The expansion chamber 181 is also vented at 183 in the side wall of the lower interrupting element 55.

The operation of the interrupter is as follows. Assuming that the operating member is in the closed circuit position, as shown in Fig. 3, and is released by the actuating mechanism 147, the accelerating springs 135 will force the operating member 81 downwardly to the position shown in Fig. 4. During the downward movement of the member 81, an arc will be drawn between each of the arcing contacts 93 and its respective fixed contact finger 75 of the respective interrupting elements 53 and 55. These arcs will bear a series relation with respect to each other by virtue of the electrical connection between the upper contact ring 89 through the conducting sleeve 101 and the flexible shunts 79 to the lower contact fingers 75. These arcs are adapted to be drawn into the notched portions 175 of the respective arc chambers 71 and held against substantial lateral movement by virtue of the stack of washers 97 which follows the arcing contact to fill in the arc chamber. The respective arcs are, therefore, confined to an elongated relatively narrow arc passage which is closed at the lower end and opened only at the upper end into the expansion chambers 177 and 181. Arc gas, generated as a result of decomposition of arc extinguishing liquid by the arc, will escape freely longitudinally of the arc into the respective expansion chambers. Escape of the gas from around the region of the arc is also accelerated by virtue of the evacuating effect produced by movement of the operating member 81. Removal of arc gases is further facilitated by the pumping action produced by the operating member 81 as it moves downwardly causing the displacement of arc extinguishing liquid longitudinally of the arc in a direction towards the respective expansion chambers. In

this manner, the pressure of arc gas is maintained low during the initial stage of arcing, thereby maintaining the arc energy at a minimum. Pressure upon the arc stream does not reach appreciable proportions until a time just prior to arc extinction. The rise in pressure which produces arc extinction results from an equalization of pressure within the expansion chambers and the arc chamber, under which condition the rate of escape of gas from the arc chamber to the expansion chamber is decreased.

The desired increase in pressure upon the arc during the final stage of arcing is further augmented by a decrease in velocity of the operating member 81 towards the end of its stroke. As the operating member 81 loses velocity due to a decrease in tension of the springs 135, the volume of the expansion chambers are increased at a rate which is less than the rate of increase in volume of gas being generated in the arc chambers. The arc pressure is also constantly increased as a result of piston action by movement of the washers 91 farther into the arc chamber 71, as a result of an increase in resistance to the flow of liquid from the arc chamber. It is, therefore, apparent that arc extinction takes place without breaking the continuity of the arc stream. This method of arc extinction avoids a rapid increase in arc voltage, sudden peaks of arc energy and the forcing of a current zero with accompanying voltage surges and mechanical shocks. The fact that the arc is confined to a passage of relatively small cross section and a flow of arc extinguishing liquid is continuously maintained longitudinally of the arc, the interrupter shows a high degree of consistency over the entire current range regardless of power factor or the type of circuit being interrupted.

Although I have shown and described a specific circuit interrupting structure, it is to be understood that the same is for the purpose of illustration and that changes and modifications may be made by those skilled in the art without departing from the spirit and scope of the appended claims.

I claim as my invention:

1. In a circuit interrupter, a quantity of arc extinguishing liquid, means of insulating material defining an elongated arc passage immersed in said liquid, said arc passage having walls which present irregular surfaces and being open only at one end, a pair of cooperating contacts at least one of which is permanently positioned outside said arc passage adjacent the open end thereof, a movable member of insulating material having irregular surfaces and supporting the other of said pair of contacts, and means for moving said member of insulating material into said arc passage to establish an arc therein, said member of insulating material displacing a portion of the arc extinguishing liquid in said passage to provide a flow of arc extinguishing liquid longitudinally of the arc toward the open end of said passage to aid in extinguishing the arc.

2. In a circuit interrupter, a quantity of arc extinguishing liquid, means of insulating material defining an arc chamber immersed in said liquid, said arc chamber being open only at one end, a grooved surface plunger member of insulating material movable into said arc chamber to provide an arc path of constricted cross section between the plunger member and a portion of the wall of said arc chamber, means cooper-

ating with said plunger member for drawing an arc from a point outside said arc chamber into the arc chamber along said constricted arc path, the products of decomposition of the arc being caused to flow longitudinally of the arc path towards the open end of said arc chamber, said plunger member displacing arc extinguishing liquid within said arc chamber to cause a flow of liquid longitudinally of the arc towards the open end of said chamber to assist in extinguishing the arc.

3. In a circuit interrupter, a quantity of arc extinguishing liquid, means of insulating material immersed in said liquid defining an arc chamber open only at one end and the inside walls of which have grooves extending therearound, a plunger member of insulating material having grooves extending therearound adapted to be moved into said arc chamber, a fixed contact adjacent the open end of said arc chamber, a cooperating contact carried by said plunger member for drawing an arc into said arc chamber, said plunger member substantially filling said arc chamber when moved therein to prevent substantial lateral movement of the arc from the position occupied when drawn and for causing a blast of arc extinguishing liquid longitudinally of the arc toward the open end of said arc chamber.

4. In a circuit interrupter, a body of arc extinguishing liquid, means of insulating material immersed in said liquid defining an elongated arc chamber and a cylindrical passage disposed side by side and having continuous communication with each other, a stationary contact disposed outside said arc chamber, a piston movable in said cylindrical passage, a cooperating contact carried by said piston and adapted to be moved therewith through said arc chamber into and out of engagement with said stationary contact, said arc chamber having a vent opening only at its end adjacent said stationary contact, and means for actuating said piston to establish an arc within said arc chamber and to cause said piston to move a quantity of arc-extinguishing liquid longitudinally of the arc toward said opening.

5. In a circuit interrupter, means defining an arc chamber, separable contacts for drawing an arc within said arc chamber, means for actuating said contacts to open and closed positions, means defining an enclosed space of variable volume adjacent said arc chamber and into which arc gases are adapted to flow, means actuated by said contact actuating means for varying the volume of said enclosed space and venting means for controlling the pressure within said enclosed space.

6. In a circuit interrupter, means defining an arc chamber, separable contacts for drawing an arc within said arc chamber, means for actuating said contacts to open and closed positions, means defining an enclosed space of variable volume adjacent said arc chamber and into which arc gases are adapted to flow, means actuated by said contact actuating means for increasing the volume of said enclosed space during the initial stage of arcing at a rate greater than the rate of increase in volume of gas being generated in said arc chamber and means for venting said enclosed space.

7. In a circuit interrupter, means defining an arc chamber, separable contacts for drawing an arc within said arc chamber, means for actuating said contacts to open and closed positions, means

defining an enclosed space of variable volume adjacent said arc chamber and into which arc gases are adapted to flow, and means actuated by said contact actuating means for increasing the volume of said enclosed space during the initial stage of arcing at a rate greater than the rate of increase in volume of gas being generated in said arc chamber, said last named means causing the volume of said enclosed space to increase during the final stage of arcing at a rate less than the rate of increase in volume of gas generated by the arc.

8. In a circuit interrupter, a body of arc extinguishing liquid, means defining an arc chamber immersed in said liquid, separable contacts at least one of which is movable for drawing an arc in said arc chamber, means defining a venting chamber adjacent said arc chamber into which arc gas from said arc chamber is adapted to flow, and an operating member extending through said arc and venting chambers for actuating said movable contact and causing arc extinguishing liquid to flow longitudinally of the arc in a direction opposite to the direction of contact movement, said operating member causing a reduction in hydrostatic pressure on the arc during the initial arcing period to facilitate the flow of gas into the venting chamber and a sudden increase in hydrostatic pressure near the end of the arcing period for raising the reignition voltage.

9. In a circuit interrupter, a body of arc extinguishing liquid, an enclosure immersed in said liquid, an arc chamber within said enclosure, an expansion chamber within said enclosure adjoining said arc chamber, a stationary contact adjacent one end of said arc chamber, a moving contact adapted to cooperate with said stationary contact, a movable contact carrying member extending through said arc chamber and having a portion normally extending into said expansion chamber, means for actuating said contact carrying member to separate said contacts to establish an arc in said arc chamber and to move the portion of said contact carrying member within said expansion chamber into the arc chamber, the portion of said contact carrying member moved into said arc chamber being so proportioned with respect to the arc chamber that the arc is confined to a narrow elongated path therein and the pressure within the expansion chamber is materially reduced upon movement of the contact carrying member therefrom at least during the initial stage of the arc extinguishing operation, and venting means for controlling the pressure within said expansion chamber.

10. In a circuit interrupter, a body of arc extinguishing liquid, an enclosure immersed in said liquid, an arc chamber within said enclosure, an expansion chamber within said enclosure adjoining said arc chamber, a stationary contact adjacent one end of said arc chamber, a piston member normally within said expansion chamber and movable into said arc chamber, a movable contact carried by said piston member and adapted to cooperate with said stationary contact, means for moving said piston member into said arc chamber to establish an arc therein and to force arc extinguishing liquid in a direction longitudinally of the arc towards said expansion chamber, said piston member upon movement out of said expansion chamber causing a reduction in pressure therein to aid the products of decomposition of the arc within the arc chamber to flow into the expansion chamber to prevent

the formation of pressures within the arc chamber during the initial arcing period detrimental to arc extinction, and means for venting said expansion chamber.

11. In a circuit interrupter, a body of arc extinguishing liquid, means within said liquid defining an arc chamber open at one end, an expansion chamber communicating with the open end of said arc chamber and said expansion chamber being otherwise substantially closed except for the vent means set forth below, a plunger member movable from said expansion chamber into said arc chamber, means for simultaneously drawing an arc within said arc chamber and moving said plunger member into said arc chamber, said plunger member confining the arc to a relatively constricted path longitudinally of said arc chamber and subjected it to a longitudinal flow of liquid, and relatively restricted vent means for said expansion chamber cooperating with the movement of said plunger member out of said expansion chamber to prevent the rise of pressure above a predetermined value within said arc chamber during the initial stage of arcing.

12. In a circuit breaker, an interrupting unit comprising a stationary and a movable part arranged to form a plurality of serially associated interrupting elements, said stationary and said movable parts having alternate sections of conducting and insulating material disposed in end-to-end relation, separable contact means arranged to interconnect the conducting sections of said stationary and said movable parts to form a conducting circuit through said unit when said conducting sections are disposed in staggered relation, said movable part having at one end of each section of insulating material an enlarged portion acting as a piston, and means for moving said movable part to break the electrical connection between said conducting sections to establish a plurality of serially related arcs and to bring the insulating sections of said moving part to a position opposite the insulating sections respectively of said stationary part for drawing and confining each arc in the space between an insulating section of the movable part and an insulating section of the stationary part.

13. In a multiple break circuit interrupter, a body of arc extinguishing liquid, means within said liquid defining a plurality of arc chambers disposed in alignment, a fixed contact adjacent one end of each of said arc chambers, an operating member movable through said arc chambers, a cooperating movable contact for each fixed contact carried by said operating member, said operating member having a plurality of enlarged portions each of which is normally disposed outside of a respective arc chamber when said fixed and moving contacts are in engagement, and means for actuating said operating member to establish an arc in each arc chamber and to move said enlarged portions of said operating member into their corresponding arc chambers, said enlarged portions upon movement into said arc chambers cooperating therewith to confine said arcs to fixed paths and subject the arcs to a longitudinal flow of arc extinguishing liquid.

14. In a multiple break circuit interrupter, a body of arc extinguishing liquid, a tubular casing immersed in said liquid, means dividing said casing into a plurality of expansion and arc chambers alternately disposed longitudinally of said casing, an operating member extending

through said chambers and closing one end of each of said arc chambers, the other end of each arc chamber being open and communicating with an expansion chamber, a fixed contact adjacent the open end of each of said arc chambers, a cooperating movable contact for each fixed contact carried by said operating member, a piston for each arc chamber carried by said operating member and disposed outside its respective arc chamber when said fixed and movable contacts are in engagement, and means for actuating said operating member to establish an arc in each of said arc chambers and to move said piston from their respective expansion chambers into their arc chambers, said pistons driving a quantity of arc extinguishing liquid from said arc chambers longitudinally of the arcs into said expansion chambers and lowering the pressure within said expansion chambers to assist the products of decomposition of said arcs to escape into said expansion chambers.

15. In a circuit interrupter, an arc chamber, separable contacts for establishing an arc within said chamber, a movable member extending through said arc chamber for actuating at least one of said contacts, and a closure for one end of said arc chamber having an aperture therein through which said movable member is adapted to slide, said closure having a portion surrounding said aperture which tapers inwardly with respect to said chamber and towards said movable member to provide a scraping edge for removing particles of decomposition of the arc from said member.

16. In combination, a shaft, means for reciprocating said shaft, and guide means through which said shaft is adapted to slide, said guide means having a portion tapering towards said shaft to provide a scraping edge circumferentially thereof for removing foreign matter from the shaft and preventing it from binding in said guide means.

17. In a circuit interrupter, a quantity of arc-extinguishing liquid, a plurality of washers of insulating material immersed in said liquid and disposed to form an arc passage, alternate washers having different internal diameters to provide a corrugated wall defining said arc passage, separable contacts adjacent one end of said arc passage, a movable member including a stack of washers of insulating material for carrying at least one of said contacts, alternate washers comprising said movable member being of different external diameter to provide a corrugated external surface, and means for moving said movable member into said arc passage to establish an arc therein and to provide a flow of arc extinguishing liquid longitudinally of the arc to aid arc extinction, at least a plurality of washers comprising said movable member having a thickness different than a plurality of the washers defining said arc passage to prevent interlocking of said movable member with the side walls of said arc passage as the result of lateral thrusts upon said movable member during its movement into and out of said arc passage.

18. In a circuit interrupter, a quantity of arc-extinguishing liquid, means of insulating material defining an elongated arc passage immersed in said liquid, said arc passage having alternate 70 grooves and ridges therein, a pair of cooperating contacts, at least one of which is positioned adjacent one end of said arc passage, a movable member at least partially of insulating material having alternate grooves and ridges thereon and 75

supporting the other of said contacts, and means for moving said movable member into said arc passage to establish an arc therein and to cause a flow of arc-extinguishing liquid longitudinally of the arc to aid in extinguishing the arc, said grooves and ridges in said arc passage being so proportioned and arranged with respect to the grooves and ridges on said movable member that interlocking of said movable member with the side walls of said arc passage is prevented.

19. In a circuit interrupter, a quantity of arc-extinguishing liquid, means of insulating material defining an elongated arc passage open only at one end and immersed in said liquid, a pair of 15 cooperating contacts, at least one of which is positioned adjacent the open end of said arc passage, a movable member at least partially of insulating material supporting the other of said contacts, and means for moving said movable member and its associated contact into said arc passage to establish an arc therein, said movable member being closely fitted with respect to the side walls of said arc passage except for a relatively small area adjacent said movable contact to cause substantially all the arc-extinguishing liquid displaced by said member during movement thereof into said arc passage to flow longitudinally of the arc toward the open end of said passage.

20. In a circuit breaker, an interrupting unit comprising a stationary and a movable part arranged to form a plurality of serially associated interrupting elements, said stationary and movable parts having alternate sections of 30 conducting and insulating material, means of insulating material for holding the alternate sections of conducting and insulating material of said movable part together, separable contact means arranged to interconnect the conducting sections of said stationary and said movable parts to form a conducting circuit through said unit when said conducting sections are disposed in staggered relation, and means for moving said movable part to break the electrical connection 35 between said conducting sections to establish a plurality of serially related arcs and to bring the insulating sections of said moving part to a position opposite the insulating sections of said stationary part for drawing and confining each 40 arc in the space between two opposed insulating sections.

21. In a circuit interrupter, an arc chamber, stationary contact means in said arc chamber, a movable contact member coacting with said 55 contact means, said contact member comprising two coaxial separable sections, at least a portion of both sections being within said arc chamber when the interrupter is in the closed position, and means operating said contact member to open circuit position to establish a circuit interrupting arc in said chamber between said contact means and one of said sections and subsequently separate said sections to establish an isolating break outside said chamber.

22. In a circuit interrupter, an arc chamber, stationary contact means in said arc chamber, a movable contact member coacting with said contact means, said contact member comprising two coaxial separable sections operable at least in part through an opening in one end of said arc chamber, at least a portion of both sections being within said arc chamber when the interrupter is in the closed position, and means operating said contact member to open circuit position to establish a circuit interrupting arc in

said chamber between said contact means and one of said sections and subsequently separate said sections to establish an isolating break outside said chamber, said separable sections coacting with each other and said arc chamber to seal the opening therein during the circuit opening operation of the interrupter.

23. In a circuit breaker, an interrupting unit comprising a stationary and a movable part arranged to form a plurality of serially associated interrupting elements, said stationary and said movable parts having alternate sections of conducting and insulating material, separable contact means arranged to interconnect the conducting sections of said stationary and said mov-
